L. J. LEON

BIRDCAGE

Filed June 23, 1924

Inventor
L. J. Leon
By *Augus Cwane Atty.*

UNITED STATES PATENT OFFICE.

LEWICKI J. LEON, OF CHICAGO, ILLINOIS.

BIRDCAGE.

Application filed June 23, 1924. Serial No. 721,678.

To all whom it may concern:

Be it known that I, LEWICKI J. LEON, a citizen of the United States, residing at Chicago, in the county of Cook and State of Illinois, have invented new and useful improvements in Birdcages, of which the following is a specification.

This invention relates to bird cages.

The main object of my invention is to so construct the base of the cage that it may be made either of sheet metal or of a relatively light, non-metallic material, such as pyroxylin, celluloid, or the like, thus enabling the base to be made light in weight, less expensive to manufacture, easy to keep clean and sanitary, and of any desired color without finishing due to the fact that the material last mentioned is supplied commercially in different colors or tones.

The invention consists further in the matters hereinafter described and more particularly set forth in the appended claims.

In the accompanying drawings—

Fig. 1 is a side view of a bird cage with a base embodying the features of my invention;

Fig. 2 is a bottom plan view of the base;

Fig. 3 is a top plan view of the removable bottom wall;

Fig. 4 is a vertical sectional view taken on line 4—4 of Fig. 2;

Fig. 5 is a perspective view of a part of the marginal wall of the base to show a detail of construction to be hereinafter described.

As illustrated in Fig. 1, the cage comprises a body 1 and a base 2, both circular in form and with the top of the cage body dome-shape, as shown in Fig. 1.

The base 2 has an upright marginal wall 3 made in the form of an annular band from a single strip of material, such as sheet metal or pyroxylin, celluloid, or the like. After being bent to form, the band 3 has its meeting ends secured together in any suitable manner, as by rivets 4, 4, as shown in Fig. 1. The marginal wall 3 being in strip form is open clear through and beads 5, 6 are provided at or adjacent the upper and lower edges of said wall.

The cage body 1 consists of spaced wires 7, 7 secured to a member or ring 8 at their lower ends, as shown in Fig. 4. The ring 8 is flat and arranged horizontal so it has a portion outside of the wires 7 for entering the channel formed by the upper bead 5

on the wall 3. In assembling, the strip 3 is applied about the ring 8 and its ends fixed together to lock the ring 8 in the bead 5 and hold the base 2 and cage body 1 against separation.

The base 2 has a bottom wall 9 made flat and of a shape to conform to the shape of the opening made by the wall 3. As shown in the drawings, the wall 9 is circular in shape and has an upstanding marginal flange 10 which fits inside the wall 3 when the bottom wall is closed and may support a tray (not shown).

To open the base 2 for the removal of the tray or for cleaning the inside of the wall 3 and the bottom wall 9, if a tray is not used. I provide a releasable connection between the bottom wall 9 and the marginal wall 3. This, as shown in the drawings, includes a plurality of projections 11, 11 on the bottom wall 9. These projections are spaced apart circumferentially and are preferably formed by bulging out portions of the flange 10. These projections or bosses 11 are of a shape and size to readily enter the channel or groove formed by the lower bead 6 and, when in said channel, hold the bottom wall in place.

To remove the bottom wall 9, it is engaged from beneath and turned sufficiently to bring its projections 11, 11 in register with a like number of notches 12, 12, formed in the lower flange *a* of the bead 6. When these parts register, the bottom wall 9 will drop out of the base 2 without necessitating separation of the base from the cage body for removal of the tray or to reach the inside of the cage for cleaning or any other purpose. The base 2 is closed by replacing the bottom wall 9. This is done by passing the projections 11 back through the notches 12 and turning the bottom wall to carry the projections into the channel of the bead 6 beyond the notches.

The structures shown and described permit making the base either of metal or a non-metallic material, such as pyroxylin, celluloid, or the like. This material is furnished commercially in varied colors, and therefore allows the making of bases of different colors to harmonize with the color scheme of the cages. The bottom wall 9 of the cage shown in Figs. 1 to 3 may be readily removed and replaced without disturbing the bird in the cage, inasmuch as the connections are all below the upper edge

of the base and permit opening the base without disconnecting it from the cage body.

I do not wish to be limited to the details of structure shown and described, for such may be variously changed and modified without departing from the spirit and scope of my invention.

I claim as my invention:

10 1. A base for bird cages, comprising a marginal wall and a separable bottom wall, and means releasably connecting said walls together, said means consisting of projections on one part entering a channel on the 15 other, with spaced openings in the channel to allow the projections to pass through on removing the bottom wall from and inserting it back in the base.

2. A circular base for bird cages, comprising a marginal wall and a separable bottom wall, said marginal wall having an inwardly opening channel with spaced, downwardly opening notches, said bottom wall having a plurality of spaced projections 25 extending outward therefrom to enter the channel for releasably holding the bottom wall in the base, said projections being brought into register with the notches on turning the bottom wall relatively to the 30 marginal wall for removal of the bottom wall from the base.

3. A circular base for bird cages, comprising a marginal wall and a separable bottom wall, said marginal wall having a

bead at its lower edge forming an inwardly opening channel, the latter having spaced notches in its lower flange, said bottom wall having an upright marginal flange provided with a plurality of spaced projections bulged outward therefrom to enter the channel for releasably holding the bottom wall in the base, said projections being brought into register with the notches on turning the base and bottom wall relatively to each other for removal of the bottom wall from the base.

4. A bird cage, comprising a cage body and base, both circular in shape, said base having a marginal wall and a separable bottom wall, said marginal wall having beads 50 at its upper and lower edges forming inwardly opening channels, a ring around the lower edge of the cage body retained in said upper channel, said bottom wall having a plurality of spaced projections to enter the 55 lower channel for releasably holding said bottom wall in the base, said lower channel having spaced notches in its lower flange, said projections being brought into register with said notches on turning said bottom wall with respect to the marginal wall for the removal of the bottom wall from said base.

In testimony that I claim the foregoing as my invention, I affix my signature, this 60 20th day of June, 1924.

LEWICKI J. LEON.
